UNITED STATES PATENT OFFICE.

HARRY JOHN SHORT, OF EAGLE GROVE, IOWA.

DESIGN FOR A TOY.

Application filed August 26, 1925. Serial No. 14,588. Term of patent 3½ years.

To all whom it may concern:

Be it known that I, HARRY J. SHORT, a citizen of the United States, and a resident of Eagle Grove, in the county of Wright and State of Iowa, have invented a certain new, original, and ornamental Design for a Toy, of which the following is a specification, reference being had to the accompanying drawing, forming part thereof.

I claim:

The ornamental design for a toy, as shown.

Des Moines, Iowa, August 21, 1925.

HARRY JOHN SHORT.
